UNITED STATES PATENT OFFICE.

BARNEY JAGIELSKI, OF ST. CLOUD, MINNESOTA.

PIPE-WRENCH.

1,264,077.

Specification of Letters Patent. Patented Apr. 23, 1918.

Application filed January 30, 1917. Serial No. 145,483.

To all whom it may concern:

Be it known that I, BARNEY JAGIELSKI, a citizen of the United States, residing at St. Cloud, in the county of Stearns and State 5 of Minnesota, have invented new and useful Improvements in Pipe-Wrenches, of which the following is a specification.

This invention relates to improvements in pipe wrenches, and has for its object to 10 simplify and improve the existing art by producing a wrench of this character constructed of few parts which may be cheaply operated and which may be easily and quickly manipulated.

15 With the above and other objects in view the improvement resides in the construction, combination and arrangement of parts set forth in the following specification and falling within the scope of the appended claims.

20 In the drawing:

Figure 1 is a side elevation of a wrench constructed in accordance with the present invention, illustrating by the dotted lines the arrangement of parts when one of the 25 jaws is to be adjusted with respect to the other jaw,

Fig. 2 is a sectional view approximately on the line 2—2 of Fig. 1, and

Fig. 3 is a sectional view approximately 30 on the line 3—3 of Fig. 1.

The numeral 1 designates the outer or stationary jaw of the wrench, the same having its inner engaging face provided with transversely disposed teeth 2, and the said jaw 35 being formed with an angular extension providing the shank 3.

The numeral 4 designates a nut, the same being provided with a pair of spaced extending ears 5—5 which are adapted to 40 straddle the end of the shank 3 and to be pivotally connected thereto, as at 6. The movable jaw is indicated by the numeral 7 and includes a flat member having its outer or engaging face of an arcuate formation as indicated by the numeral 8, and the ends of the said jaw 7 are centrally slotted, as indicated by the numerals 9—9, one of the said slotted ends adapted to engage with the opposite sides of the shank 3 when the de-

vice is in operative position, as illustrated 50 by the full lines in Fig. 1. Formed with the jaw 7 and extending centrally from the inner or rounded face thereof is a shank 7' which is preferably rounded in cross section and which is provided with threads 11 55 that engage with the threads in the bolt 4, while the end of the shank 10 is integrally formed with a handle member 12 that is preferably flat and rectangular in cross section.

To adjust the jaws 7 with relation to the jaw 1, the handle 12 is grasped by one hand of the operator, the shank of the jaw 1 being grasped by the other hand, and the handle is swung with the nut 4 on the pivot 6 and 60 turned or screwed upon the nut to bring the jaw 7 either toward or away from the jaw 1. One of the slotted ends 9 of the jaw 7 is arranged to receive the inner edge and opposite sides of the shank 3 when the handle 12 65 is swung upon the fulcrum pin 4 to bring the jaw 7 in the direction of the said shank 3, and the operation as well as the simplicity of the construction, will, it is thought, be apparent. The jaw 7 is illustrated as of less 70 width than the length of the jaw 1, but the said jaw 7 may be larger than shown. In operation, however, the arched surface 8 of the jaw 7 is at all times arranged directly 75 inward, and as in the position illustrated in Fig. 1 of the drawings, directly below the jaw 2.

Having thus described the invention, what I claim is:

1. In a wrench, the combination with a 85 stationary jaw and a movable jaw which has its shank pivoted and longitudinally adjustable with respect to the stationary jaw, said movable jaw having an arched head and having its opposite edges notched and said 90 notches designed to engage with the shank of the stationary jaw, when the said notched ends of the movable jaw are brought opposite the said shank, whereby to lock the movable jaw on the shank of the stationary 95 jaw against transverse movement.

2. In a wrench, the combination with a stationary jaw and a movable jaw, said sta-

tionary jaw having at one of its ends a right angular cross sectional rectangular shank, the movable jaw having a shank arranged to one side of the shank of the stationary 5 jaw and revolvably and longitudinally adjustable with respect to the stationary jaw, said movable jaw having a widened head,

the active surface of which being arched and the ends of the said head being notched whereby to receive in one of the notches the shank of the stationary jaw.

In testimony whereof I affix my signature.

BARNEY JAGIELSKI.
